UNITED STATES PATENT OFFICE.

HARRY A. WARDY, OF KALAMAZOO, MICHIGAN, ASSIGNOR TO WALTER M. BLINKS,
TRUSTEE, OF KALAMAZOO, MICHIGAN.

FILING-CABINET.

1,146,464.

Specification of Letters Patent. Patented July 13, 1915.

Application filed September 22, 1913. Serial No. 791,253.

To all whom it may concern:

Be it known that I, HARRY A. WARDY, a citizen of the United States, residing at the city of Kalamazoo and State of Michigan, have invented a new and useful Filing-Cabinet, of which the following is a specification in such full, clear, and precise language as will enable those skilled in the art to understand the same.

10 This invention relates to filing cabinets and consists in the novel arrangement and combination of parts shown and described.

An object of the invention is to provide a suitable filing case wherein folders or cards 15 may be placed in any systematic order and to provide in connection therewith a selecting device, whereby predetermined ones of the folders and cards may be withdrawn irrespective of their positions in the case.

20 Another object of the invention is to provide a convenient form of mechanism for readily and accurately adjusting the selecting device.

With these and other objects in view, I 25 have constructed a filing cabinet consisting of the several parts hereinafter described and illustrated in the drawings in which—

Figure 1 is a plan view of the cabinet, showing one of the sides thereof open. Fig. 30 2 is an enlarged detail fragmentary plan view of the principal operating parts of the selecting device. Fig. 3 is a transverse sectional view taken substantially on the line 3—3 of Fig. 1. Fig. 4 is a side view of the cabinet, showing the side thereof in normal 35 or raised adjustment. Fig. 5 is a detail fragmentary view, taken substantially on the line 5—5 of Fig. 4, more particularly illustrating the operating handle or lever 40 for the selecting device and its immediately associated parts. Fig. 6 is an enlarged detail view, showing a fragmentary horizontal section, substantially on the line 6—6 of Fig. 4, illustrating particularly the hinging of 45 the bail constituting a portion of the selecting device.

In the preferred embodiment illustrated in the drawings, A indicates a cabinet or case constructed preferably of metal and 50 comprising front and end walls 1, a bottom wall 2 and side walls 3; each of the side walls has a hinged connection with the bottom wall 2 as indicated at 4. A tractile spring 5 is provided at either side of the rear

of the case; one end of each of said springs 55 being fixed to the bottom wall remote from the side and the other end of each of said springs being secured to each of the side walls 3, respectively. The tendency of said springs is to actuate said side walls to vertical or closed position, as will be readily understood. Longitudinal blocks 6 are secured to the bottom of the cabinet adjacent to each side thereof; said blocks having their side faces inclined slightly outwardly, and 60 constituting guides for the folders or cards placed in the cabinet. The width of the cabinet between the inner faces of said guides 6 is substantially that of the width of the folders or cards which are designed to 65 be placed in the cabinet, thus the folders or cards are maintained in substantial alinement when placed between said guides.

In the embodiment illustrated it is contemplated that the folders or cards be arranged in the cabinet or case in alphabetical order and that the folders or cards be selected and withdrawn in the calendarial or numerical order. The folders or cards are provided at each side thereof, and upon their 75 front face, with indicating characters such, for instance, as consecutive numbers indicating the respective days of the month. I have illustrated, for the purpose of convenience, the folders or cards with the numbers from 1 to 15 inclusive, on one side and from 15 to 31 inclusive on the opposite side, making a complete monthly index. When the folders or cards are filed in alphabetical arrangement and it is desired to withdraw 80 selected ones thereof say, for instance, on the ninth day of the month, the removable hook 7, which comprises a clamping body portion 85 and a hook extension, is adjusted upon the edge of the folder or card so that the desired 85 date will appear through the open space of the body portion of the hook as is clearly shown in Fig. 3 at the time the folder or card is filed. All the folders or cards are provided with uniformly positioned index 90 characters, so that when filed all of the hooks for a given date will be in longitudinal alinement and will, therefore, be in position to be engaged by the selecting rod when adjusted for such predetermined date in the 95 manner hereinafter described.

The selecting device that is carried by each of the side walls, comprises a rod 100

provided at each end with an outwardly projecting lip 12 which is hinged or pivoted to a guide plate or bearing member 13, which is adapted to slide vertically in slots 14, formed in the side walls near each end thereof, as clearly appears in Fig. 1 of the drawings. The said rod 11 is provided with an arm or thumb plate 15 which extends upwardly and outwardly therefrom through a slot 16 in the side wall of the case. The rod 11 is provided with a bail which extends inwardly and in normal adjustment, obliquely downwardly therefrom, comprising a rod 17 supported in parallel adjustment to the rod 11 by angular integral arms 18; said arms 18 being united at their inner ends to the rod 11 adjacent to each extremity of said rod 11, respectively. The arrangement of these parts will be clearly apprehended from the illustration thereof included in Fig. 1 of the drawings.

Near the bottom of each of the side walls, substantially intermediate of their ends, is secured a bracket 19 in which are journaled short shafts or pins 20; the said pins or shafts 20 carry meshing segmental spur gears 21; each of said gears has secured thereto, a radially extending arm 22; and each of said arms is provided at its outer end with an ear or extension 23, which has pivotal connection with a movable collar 24 encircling the rod 11, as is clearly shown in Fig. 1 of the drawing. One of the pins or shafts 20 extends through the side of the cabinet and is provided at its outer end, with an arm 25. The arm 25 constitutes an indicating device as well as an operating handle for raising and lowering the selecting bail. It is apparent that as the handle 25 is moved through the arc indicated by the graduated scale 26, that the rod 17 through its connections will be correspondingly positioned, for instance, if it is desired to engage all folders or cards whose hooks have been positioned upon the folders or cards at the place indicated by the numeral 9, the arm 25 is moved to the position indicated on the scale by the corresponding numeral 9 which through the graduated connections moves the rod 17 in a position to engage the hooks so positioned on the folders or cards.

For the purpose of readily engaging and operating the arm 25 said arm is provided with a suitable thumb or finger seat 27; and for preventing accidental misplacement of the arm after adjustment, a series of perforations or holes 28 are provided in which an inwardly extending pin 29, carried by the arm 25, is seated by inward pressure due to the flexibility of the arm 25, after it has been moved to proper position.

After the rod 17 has been brought to the desired position through the mechanism described, the shaft 11 is rocked by manipulation of the arm or thumb plate 15, raising

the rod 17 from its normally downwardly inclined position to a horizontal adjustment, thereby engaging all hooks with which it is alined. After thus engaging the hooks the side of the cabinet or case may be pulled outwardly, which movement lifts from their position in the cabinet all the folders or cards thus engaged by the selecting device, and carries them over to the side of the cabinet as shown in Fig. 1.

From the foregoing description it will be apprehended that the present invention is very useful where the follow-up system, so-called, is employed, for the reason that the folders or cards may be filed in the usual alphabetical order, and may be simply and accurately selected and withdrawn from the cabinet in predetermined classes, without disturbing the arrangement of the remaining folders or cards contained in the cabinet.

I am aware that modification in the structure, within equivalent limits, may be made without departing from the general spirit and scope of the invention. I do not limit myself, therefore, to exact details, but

What I claim and desire to secure by Letters Patent is:

1. In a filing cabinet arranged to contain folders, the combination with a hinged wall, of engaging members adapted to be adjusted at selected positions on said folders, a selecting device carried by said wall, a mechanical device for positioning said selecting device in position to engage selected ones of said engaging members, and an arm for raising said selecting device to engage said engaging members.

2. In a filing cabinet, the combination with a number of folders or cards arranged in said cabinet in a predetermined order, engaging members adapted to be adjusted in different positions on said folders, a hinged wall, a selecting device carried by said hinged wall, and mechanical means for selectively adjusting said selecting device, substantially as specified.

3. In a filing cabinet, the combination with a plurality of folders or cards, a hinged wall, means operable to connect said wall with said folders or cards, and a mechanical device for selectively adjusting said connecting means, substantially as specified.

4. In a filing cabinet, the combination with a plurality of folders arranged therein in predetermined order, a pivoted support constituting a wall of said cabinet, engaging members arranged to be selectively positioned on said folders or cards, means carried by said support operable to engage with selected ones of said engaging members, and a mechanical device for selectively positioning said engaging means.

5. A filing cabinet provided with a hinged wall, a bail slidably carried by said wall, folders or cards in said case, hooks adapted

- to be selectively positioned on said folders or cards, and mechanical means for positioning said bail to engage selecting ones of said hooks, substantially as specified.
- 5 6. In a filing cabinet, the combination with a plurality of folders or cards, of engaging members adapted to be adjusted upon said folders or cards, a movable support, a shaft carried by said support and arranged to be 70
10 adjusted vertically to different positions, a bail on said shaft, means for rocking said shaft effectively to engage said bail with said engaging members, and a mechanical device for raising and lowering said shaft, 75
15 substantially as specified.
7. A filing system comprising a case, a series of folders or cards arranged in said case, adjustable engaging members adapted to be adjusted in different positions on said 80
20 folders or cards, a selecting device supported by one of the walls of said case, mechanical means for positioning said selecting device, and a handle projecting through one wall of said case for operating said selecting 85
25 device to engage the engaging members carried by said folders or cards.
8. A filing cabinet arranged to contain folders or cards and comprising a bottom and end walls, a support hinged to said bottom 90
30 wall, co-acting arms supported by said support, a shaft supported by said arms, a bail carried by said shaft, means for raising and lowering said arms and thereby said shaft, engaging members carried by the 95
35 folders or cards, and means for rocking said shaft effectively to engage said bail with said engaging members carried by said folders or cards, substantially as specified.
9. In a filing cabinet arranged to contain 40
40 folders or cards, the combination with a hinged wall and resilient means for maintaining said wall normally in vertical position, of a shaft slidably supported by said wall, a bail carried by said shaft, engaging 45
45 members carried by the folders or cards in said cabinet, means for raising and lowering said shaft, an actuating device for guiding the operation of said means, and a handle for rocking said shaft effectively to cause 50
50 said bail to engage with selected ones of said engaging members carried on the folders or cards, substantially as specified.
10. The combination with a plurality of 55
55 folders or cards and adjustable hooks carried thereby, of a hinged support arranged adjacent to the hooks carried by said folders, a selecting device adjustably carried by said support, mechanical means for adjusting said selecting device, and means for operating said selecting device to engage selected ones of said hooks, substantially as specified.
11. In a filing cabinet arranged to contain 60
60 cards and folders, a hinged wall at one side 65
65 of the cabinet, interconnected levers pivoted upon said wall, a rock shaft supported by said levers, an actuating lever for operating said levers effectively to move said rock shaft vertically adjacent to said wall, an engaging device supported by said rock 70
75 shaft, and means for rocking said shaft effectively to move said engaging device into engagement with projections on said cards and folders.
12. A filing cabinet comprising a cabinet 75
75 arranged to contain cards and folders, a pivoted wall closing one side of said cabinet, interconnected supports pivoted upon said wall, bearings carried by said supports, a rock shaft or rod journaled in said bearings, 80
80 a lever for actuating said supports effectively to move said rock shaft vertically, an engaging device supported by said rock shaft, and means for rocking said shaft effectively to move said engaging device into 85
85 engagement with projections on said cards and folders.
13. In a filing cabinet, the combination with series of cards and folders deposited in the cabinet, and projections extending laterally from said cards and folders, of a device operable to engage with predetermined ones of said projections, means for positioning said device to engage any desired ones of said projections, means for preventing 90
90 accidental change of position of said engaging device, a hand lever operable to engage said engaging device with said projections, and an indicator controlled by said engaging device designating what series of hooks 95
95 said engaging device it is positioned to engage.
14. In a filing cabinet, a wall hinged at one side of said cabinet, levers pivoted to said wall, bearings pivoted to said levers, a 100
100 rockable support journaled in said bearings, means for actuating said levers to move said rockable support vertically, a latching device for preventing accidental movement of said levers, and a bail carried by said rockable support, for the purpose set forth.
15. In a filing cabinet, the combination with a hinged wall at one side of the cabinet, of a bail supported by said hinged wall for vertical adjustment and movement from the 110
110 wall, a manipulative device for moving said bail vertically with respect to said wall, and means for actuating said bail away from said wall.
16. In a filing cabinet, the combination 115
115 with a support hinged at one side of said cabinet and movable to and from a vertical position, of a bail carried by said support for vertical adjustment and movement from the support, a device for moving said bail 120
120 vertically to different positions with respect to said support, and a lever for actuating said bail inwardly from said support, substantially as described.
17. In a filing cabinet, the combination 125
125

- with a support hinged at one side of said cabinet, and means for holding said support in a vertical position, of a bail carried by said support for vertical adjustment and movement from the support, a manipulative member for moving said bail vertically to different positions with respect to said support, means for preventing accidental displacement of said bail from any of the positions to which it may be moved as aforesaid, and an independently operable device for actuating said bail inwardly from said support, substantially as described.
18. In a filing cabinet, the combination with a support hinged at one side of said cabinet and movable to and from a vertical position, and means for holding said support in a vertical position at the side of said cabinet, of movable bearings supported by said support, a bail supported by said bearings, means for actuating said bearings to move said bail to different vertical positions, and means for actuating said bail inwardly from said support, substantially as described.
25. 19. In a filing cabinet, the combination with a support hinged at one side of said cabinet and movable to and from a vertical position, and means for holding, said support in a vertical position at the side of said cabinet, of a bail, means for supporting said bail in connection with said support for vertical adjustment and movement from the support, manipulative means for moving said bail vertically to different positions, and means for actuating said bail inwardly from said support.
20. In a filing cabinet, the combination with a support hinged at one side of said cabinet, a swinging bail carried by said support for vertical adjustment and movement from the support, means for actuating said bail inwardly from said support, and independent means for moving said bail vertically to different positions.
45. 21. In a filing cabinet, the combination with a plurality of folders or cards, and engaging members in connection with said folders or cards, of a support hinged at one side of said cabinet, a bail movably carried by said support, and a lever for actuating said bail into engagement with said engaging members, substantially as described.
55. 22. In a filing cabinet, the combination with a plurality of folders supported within the cabinet, and engaging members on said folders, of a support hinged at one side of said cabinet and movable to and from a vertical position, a bail pivotally supported by said support, and mechanical means for moving said bail in the direction away from said support and into engagement with said engaging members.
60. 23. In a filing cabinet, the combination with a number of folders or cards supported within the cabinet, a support hinged at one side of said cabinet and movable to and from a vertical position, of a member carried by said support pivotally and for vertical adjustment, means for moving said member vertically to different positions, and means for actuating said member into engagement with said engaging members, substantially as described.
65. 24. In a filing cabinet, the combination of a support pivoted at one side of said cabinet and movable to and from a vertical position, and means for holding said support in a vertical position, of a device supported on said support pivotally and for vertical adjustment, means for moving said device vertically to different positions, and independent means for actuating said device away from said support, substantially as described.
70. 25. In a filing cabinet, in combination with a hinged support at one side of the cabinet and movable to and from a vertical position, and actuating means for restoring said support to vertical position after it has been moved away therefrom, of a bail carried by said support pivotally and for vertical adjustment, means for moving said bail vertically to different positions, and independent means for actuating said bail away from said support, substantially as described.
75. 26. In a filing cabinet arranged to contain cards and folders, a hinged wall at one side of the cabinet, a lever pivoted upon said wall, another lever pivoted upon said wall, interconnections between said levers whereby one of said levers will actuate the other, a manually engageable device for actuating one of said levers, a rock shaft supported by said levers, an engaging device supported by said rock shaft, and means for rocking said shaft effectively to move said engaging device into engagement with projections on said cards and folders.
80. 27. In a filing cabinet arranged to contain cards and folders, a hinged wall at one side of said cabinet, interconnected levers pivoted upon said wall, an engaging device shiftable toward and from the hinge axis and controlled by said levers, an actuating lever for operating said levers to shift said engaging device, and means for moving said engaging device into engagement with projections on said cards and folders.
85. In witness whereof, I have signed this specification in the presence of two subscribing witnesses.
